UNITED STATES PATENT OFFICE.

ROY L. BOWMAN, OF TOLEDO, OHIO.

MECHANICAL TOY.

1,323,002.

Specification of Letters Patent. Patented Nov. 25, 1919.

Application filed April 8, 1919. Serial No. 288,577.

To all whom it may concern:

Be it known that I, Roy L. BOWMAN, a citizen of the United States, residing at Toledo, in the county of Lucas and State of Ohio, have invented certain new and useful Improvements in Mechanical Toys, of which the following is a specification.

My invention relates to mechanical toys, and has particular reference to such a device 10 wherein an animated figure, such as a monkey, is made to travel up and down a support, preferably simulating a tree.

An important object of the invention is to provide a toy of the above mentioned character, which is entirely gravity operated, and wholly automatic when set into action.

A further object of the invention is to provide a toy of the above mentioned character, formed of few and simple parts.

20 A further object of the invention is to provide a toy of the above mentioned character, which is extremely interesting in operation and has its operating parts more or less completely concealed.

25 Other objects and advantages of the invention will be apparent during the course of the following description.

In the accompanying drawings forming a part of this specification and in which 30 like numerals are employed to designate like parts throughout the same,

Figure 1 is a side elevation of a mechanical toy embodying my invention.

Fig. 2 is a plan view of the same, the base 35 being omitted.

Fig. 3 is a horizontal sectional view taken on line 3—3 of Fig. 1.

Fig. 4 is an enlarged side elevation of the monkey,

40 Fig. 5 is a horizontal sectional view taken on line 5—5 of Fig. 4.

Fig. 6 is a detail vertical section through the head of the monkey showing its mouth and ejector,

45 Fig. 7 is a transverse sectional view taken on line 7—7 of Fig. 6.

Fig. 8 is a horizontal sectional view taken on line 8—8 of Fig. 4, looking upwardly, as indicated by the arrows.

50 Fig. 9 is a perspective view, partly assembled, of the leaf carrying collar,

Fig. 10 is an enlarged plan view of the weight feeding element,

55 Fig. 11 is a detail section taken on line 11—11 of Fig. 10, and,

Fig. 12 is a side elevation of the weight

feeding device, parts being shown in longitudinal vertical section.

In the drawings, wherein for the purpose

of illustration is shown a preferred embodiment of my invention, the numeral 15 designates an upstanding tubular support, which

is preferably painted or otherwise decorated so that it simulates a tree. This tubular support is preferably formed of sheet metal

such as tin, which is bent into the tubular form with the edges of the tin crimped or hooked to interlock, as shown at 16, while

the invention is in no sense restricted to this particular construction. The tubular

support 15 has longitudinal exterior grooves

17 formed therein, preferably by bending the material thereof inwardly. A conical

collar 18 surrounds the lower portion of the tubular support 15 and may be secured

thereto by any suitable means. This collar carries a stationary upstanding trip 19, as

shown. The lower end of the support 15

projects downwardly beyond the collar 18

and is adapted for insertion through an

opening 20 formed in the top 21 of a base

22. This base is preferably hollow and has a pair of rods 23 extending across the same,

the rods crossing each other at a right angle,

as shown. The lower end of the tubular

support 15 is provided with slots 24 and 25,

to receive the rods 23, the slots 24 being

slightly longer than the slots 25, so that the

wires will seat into the upper ends of the

slots and hold the support 15 perpendicular.

90 The numeral 26 designates a collar, shown

more clearly in Figs. 1, 2 and 9. This collar is preferably formed from a section of tin

or the like, one end of which is provided

with a pair of tongues 27, adapted for inser-

tion within slots 28, the tongues being bent

back after being inserted within these slots.

The collar 26 surrounds the upper end of

the tubular support 15 and contacts with an

outwardly bulging flange 29, as shown. The

strip 26 carries an inwardly projecting

tongue 30, adapted to enter a slot 31 formed

in the upper end of the tubular support.

105 The collar 26 is provided with a plurality

of leaves 32, preferably formed integral

therewith, and extensions 33 are struck from

the material of two of these leaves, for a

purpose to be described. The collar 26

carries a radial extension 34, having a free

end portion 35. This free end portion is

adapted to be bent at a right angle to the

extension, and has a lug 36, to engage within

a slot 37, formed in an inclined trough 38, preferably simulating a leaf. This inclined trough is adapted to receive and hold a plurality of preferably spherical weights 39, which are adapted to travel longitudinally in a depression 40. There is an upwardly projecting portion 41 at the lower end of the trough or depression 40, having an opening 42 formed therein conforming to the curvature of the depression 40 and permitting of the discharge of the weights therethrough. One portion 43 of the member 41, is bent laterally, forming a stop 44, while the other portion 45 has connection 15 with a pivot element or pin 46.

As more clearly shown in Figs. 2, 10, 11 and 12, the numeral 47 designates a weight feeding device as a whole, comprising a forward pocket 48, having sides 49, apertured for receiving the pivot element 46. This pocket is provided with an outwardly projecting extension or lever 50, as shown. An outer stop shoulder 51 is stamped from the material of the pocket 48, and bent upwardly, such shoulder having a hooked portion 52, engaging the pivot element 46, to reinforce the pocket 48. The pocket 48 is slightly inclined downwardly toward its outer end, when the inner end of one side 25 thereof, engages beneath the stop 44, as clearly shown in Fig. 12. By this means, the weight 29 will rest upon the shoulder 51 and will not discharge through the opening 53, until the pocket is swung upon its pivot, 30 by means to be described. The outer side of the pocket 48 is closed while its inner side is provided with an opening 54, to register with the opening 42 when the pocket is in the normal starting position, as shown in 35 Fig. 12. This permits one weight 39 to feed into the pocket 48, but when the pocket is swung upon its pivot to discharge the weight contained therein, the opening 54 is moved out of registration with the opening 42, and the next ball or weight cannot enter the pocket until it is returned to the starting position, which is accomplished by 40 the weight of the extension 50.

The numeral 55 designates a figure, preferably simulating a monkey, the same being painted in suitable colors, as may be found advantageous. This monkey comprises a body portion 56, arms 57, legs 58 and head 59. Connected with the inner and outer 45 portions of the arms and legs are transverse shafts 60, which are preferably rotatable and carry guide wheels 61, preferably rigidly secured thereto. These guide wheels operate within the grooves 17, and permit the 50 monkey to move longitudinally of the tubular support but prevent the turning movement of the monkey with relation thereto.

As more clearly shown in Figs. 4, 6 and 7, the monkey's head 59 is provided with a 55 recess 62, constituting a mouth, and one wall

or side 63 of this recess is inclined, as shown in Fig. 7, to permit of the discharge of the weight 39, when elevated by the head 64 of an ejector rod 65. This ejector rod slides within an opening 66, and extends longitudinally of the body of the monkey and operates within an opening formed through a lower guide 67, which is preferably formed integral with the tail 68 of the monkey, such tail being securely attached to the monkey. 70 The lower end of the body portion of the monkey is hollow so that the stationary trip 19 may project into the same and contact with the lateral extension 69 of the ejector 75 80 85 90 95 100 105 110 115 120 125 130 135 140 145 150 155 160 165 170 175 180 185 190 195 198 200 202 204 206 208 210 212 214 216 218 220 1576 1577 1577 1578 1578 1579 1579 1580 1580 1581 1581 1582 1582 1583 1583 1584 1584 1585 1585 1586 1586 1587 1587 1588 1588 1589 1589 1590 1590 1591 1591 1592 1592 1593 1593

of my invention or the scope of the subjoined claims.

Having thus described my invention, I claim:

- 5 1. In a mechanical toy of the character described, a tubular upstanding support, a figure simulating a monkey to travel longitudinally of the support and having a head provided with a weight receiving mouth, 10 said figure having a laterally extending tail, a receptacle connected with the upper portion of the support to receive a plurality of weights, a pivoted feed member arranged near the receptacle to receive a weight therefrom and transfer the same to said mouth, 15 an extension secured to the pivoted member and serving to swing it to one position and being arranged in the path of travel of the tail of the monkey, a reciprocatory ejector 20 rod extending through the body of the monkey and entering the mouth to discharge the weight therefrom, a trip to engage the ejector rod and move it, and gravity operated means arranged within the tubular support 25 and connected with the monkey to move it upwardly.
2. In a mechanical toy of the character described, an upstanding support, an inclined trough connected with the upper end thereof, 30 a weight receiving device embodying a swinging pocket pivotally connected with the support and arranged at the lower outlet end of the trough, the pocket having its free end open, a weight extension connected 35 with the pocket to swing it in one direction, a stop arranged to limit the swinging movement of the pocket in one direction, a figure simulating an animal to travel longitudinally of the support and having a weight 40 receiving pocket which is adapted to receive the weight from the free end of the pocket, said figure having a laterally extending appendage to engage with the weight extension, a reciprocatory ejector rod extending 45 longitudinally of the body of the figure with its upper end projecting into the pocket, a trip to engage the lower end of the ejector rod, and means to move the figure upwardly.
3. In a mechanical toy of the character described, a tubular support, a member connected with the upper end of the tubular support and provided with a plurality of leaves, one leaf having a longitudinal inclined groove for receiving rolling weights, a vertically swinging weight feeding device pivotally connected with said member and arranged near the outlet end of said groove, said device em-
- bodying a weight receiving pocket having its free end open and one side thereof provided with an opening adapted to be brought into and out of registration with said groove, a weight-extension secured to the pocket and serving to swing the same in one direction, a stop to engage with the pocket to limit the swinging movement of the same by the 65 weight-extension and to hold the pocket in an inclined position so that the weight will not discharge from the open free end thereof, a figure simulating an animal to travel longitudinally of the support, said figure 70 having a weight receiving pocket and a laterally extending appendage, said appendage being adapted to engage with the weight-extension to swing the pocket upon its pivot, an ejector element connected with the figure and extending into the weight receiving pocket thereof, a trip arranged to engage with the ejector element, and gravity operated means to move the figure upwardly 75 arranged in the tubular support.
4. In a mechanical toy of the character described, a support, a longitudinally inclined trough connected with the upper end thereof and provided at its lower end with a closing member having an outlet opening, a weight 80 receiving device embodying a vertically swinging pocket pivotally connected with the support and arranged at the outlet opening of the trough, said pocket having its free end open and one side thereof provided with an opening adapted to be moved into and out of registration with the outlet opening of the trough, a weight-extension connected 85 with the pocket to swing the same upwardly, a stop arranged to limit the outward movement of the pocket and serving to normally maintain the same in a slightly inclined position whereby the weight is normally prevented from discharging from the open free end of the pocket, a figure simulating an animal to travel longitudinally of the support and provided with a head having a weight receiving mouth, said mouth being adapted 90 to receive the weight from the open free end of the pocket, said figure having a laterally extending appendage to engage with the weight-extension, and means to move the figure upwardly.
